UNITED STATES PATENT OFFICE.

ERWIN A. MILLIES, OF HAMMOND, INDIANA.

DOOR FASTENER.

Application filed April 18, 1922. Serial No. 554,480.

To all whom it may concern:

Be it known that I, ERWIN A. MILLIES, a citizen of the United States, residing at Hammond, in the county of Lake and State of Indiana, have invented a new and useful Door Fastener, of which the following is a specification.

This invention aims to provide novel means for holding the door of a freight car in place, thereby relieving the strain on the hasp of the door, the device being of peculiar utility, whilst the car is being bumped about during switching.

In the accompanying drawings:—

Figure 1 shows in elevation, a portion of a car equipped with the device forming the subject matter of this application; Figure 2 is a section on the line 2—2 of Figure 1; Figure 3 is a section on the line 3—3 of Figure 2.

The numeral 1 designates the wall of a freight car, the floor appearing at 2, and the sill at 3, the sill constituting a part of the framework of the car. The usual sliding door is marked by the numeral 4 and cooperates with a keeper 5.

In carrying out the invention, a keeper 6 is attached by securing elements 7 to the sill 3 and is located at the rear lower corner 30 of the door 4 when the door is closed. The keeper 6 comprises a bottom plate 8, an outer wall 9, an end wall 10, and an arm 11 projecting from the end wall 10, the arm extending parallel to the direction in which the door 4 slides. There is a vertical transverse opening 12 in the arm 11, aligned with an opening 35 in the bottom plate 8.

The inner lower corner of the door 4 is straddled by a U-shaped bracket 14 having an opening 15 adapted to receive the arm 11 of the keeper 6 when the door 4 is closed. The bracket projecting downwardly below the lower edge of the door 4. The bracket 14 is held on the door 4 by securing members 16 and 17. A guide pin 18 is inserted into the rear edge of the door 4 and has a head 19 spaced from the rear edge of the door. The guide pin 18 is provided with a transverse notch 20 receiving the securing member 16, the securing member thus having a double function, in that it retains the guide pin 18, in addition to holding the bracket 14 on the door 4.

A latch 21 is mounted for vertical reciprocation on the rear edge of the door 4 and is provided at its upper end with a finger

piece 22 facilitating the manipulation of the latch. The latch 21 is supplied with an elongated slot 23 receiving the guide pin 18, the head 19 of the guide pin holding the latch on the edge of the door 4 for vertical reciprocation. The latch 21 has a reduced end 24 adapted to extend through the opening 12 in the arm 11, and through the opening 35 in the bottom plate 8 of the keeper 6, a shoulder 26 being formed on the latch, the shoulder cooperating with the arm 11 to limit the downward movement of the latch. A recess 27 is fashioned in the outer surface of the latch 21 adjacent to the shoulder 26. The recess 27 is large enough to receive the head 19 of the guide pin 18, under circumstances which will be pointed out herein-after. In the reduced end 24 of the latch 21, an opening 25 is formed. The opening 25 is adapted to receive a seal (not shown).

In practical operation, the latch 21 is raised and moved to the right (Figure 3) until the head 19 of the guide pin is received in the recess 27 of the latch, the latch thus being held elevated. The door 4 is slid to a closed position in the direction of the arrow A, until the arm 11 on the keeper 6 is received in the opening 15 of the bracket 14. The latch 21 is pushed to the left (Figure 3) until the latch 19 of the guide pin 18 no longer registers in the recess 27 of the latch. The latch then is slid downwardly, until the reduced end 24 of the latch extends through the opening 12 in the arm 11 of the keeper 6, and through the opening 35 in the bottom plate 8 of the keeper. Then, if desired, a seal (not shown) may be mounted in the opening 25 of the latch.

When the parts are arranged as shown in Figure 3, the door 4 will be held securely against sliding movement, and the strain will be taken off the hasp of the door.

What is claimed is:—

1. In a device of the class described, a support, a door slidable on the support, a bracket on the door, a keeper on the support, and a latch slidable on the door and engageable with the keeper, the keeper comprising a part which engages the bracket, independently of the latch, to stop the movement of the door when the door is moved to a closed position.

2. In a device of the class described, a support, a door slidable on the support, a bracket on the door and having an opening, a keeper mounted on the support and in-

cluding a bottom member and an arm overhanging the bottom member, the arm being adapted to be received in the opening of the bracket when the door is closed, the member and the arm having openings, and a latch 5 slidable on the door and adapted to enter the last specified openings.

3. In a device of the class described, a support; a door slidable on the support; a bracket on the door; a securing element connecting the bracket with the door; a keeper 10 on the support and engaged with the bracket when the door is closed; a guide on the door, the guide being interengaged with the securing element, to prevent withdrawal of 15 the guide; and a latch slidable on the guide and engageable with the keeper.
4. In a device of the class described, a

support a door slidable on the support, a guide on the door, and having a head, a 20 latch slidable between the head of the guide and the door, and having an elongated slot wherein the guide is received, there being a recess in the latch, at the lower end of the slot, and adapted to receive the head of the 25 latch, when the latch is raised and moved away from the door, and a keeper on the support, wherewith a latch engages when the latch is lowered.

In testimony that I claim the foregoing 30 as my own, I have hereto affixed my signature in the presence of two witnesses.

ERWIN A. MILLIES.
